UNITED STATES PATENT OFFICE

2,625,756

FEED WATER SYSTEM FOR STEAM IRONS

Robert O. Stevenson, Philadelphia, and Charles Roger Turner, Springfield Township, Montgomery County, Pa., assignors to Proctor Electric Company, Philadelphia, Pa., a corporation of Pennsylvania

Application June 6, 1947, Serial No. 753,076

7 Claims. (Cl. 38—77)

1

This invention relates to steam irons, and more particularly to the type of combination dry and steam iron which is shown and described in the co-pending application of Stevenson et al., Serial No. 708,774 filed November 8, 1946.

In steam irons of this class, wherein water is supplied from an external source, such as an attached or built-in reservoir, the water is fed to a chamber in the sole plate and flashed almost instantly into steam. Certain prior irons, of this class which rely on gravity or other forces to supply the water to the steam chamber, have been generally unsatisfactory in that the flow of water is not even, but rather is spasmodic and irregular. This has resulted in inadequate steam supply to the fabric being ironed and has presented a problem with respect to maintenance of satisfactory steam pressure. In these prior irons, the flow of water to the steam chamber has often been affected by the surges in pressure in the steam chamber frequently backing up the water in the feed tubes from the reservoir.

It is therefore an object of this invention to provide a new and improved construction to supply a small and uniform water flow, under gravitational forces, from a reservoir to a steaming chamber in a steam iron.

Another problem in the intermittent flow of water to the steaming chamber is that of insuring that the water from a reservoir will start to flow after the iron has been used as a dry iron for some time. Often when the water is admitted into the tubes from the reservoir, the tubes have attained such a temperature as to vaporize the water before it reaches the steam chamber. This steam generation in the tubes restrains the flow of water to the steam chamber, resulting again in uneven and inadequate steam production in the steam chamber.

Another object of this invention then is to provide a feed water system that will allow immediate water flow from the reservoir to the steam chamber regardless of whether or not the iron has been in use prior to the demand for its steaming ability.

A further problem arises in steam irons of this class which are used in localities wherein the water contains alkali and mineral salts. The evaporated water precipitates or otherwise deposits the salts and minerals in the steam chamber which results, oftentimes, in clogged and plugged water supply lines or steam exhaust holes. In the past, certain steam irons have been designed with evaporation plates which were removable from the sole plate as a large

2

screw-threaded section. The precipitated salts and minerals have acted as a bonding agent to securely hold the removable plug and sole plate together. This has rendered difficult the cleaning of the iron and of otherwise servicing it.

It is, therefore, a further object of this invention to provide a new and novel method of securing the clean-out plug in a steam iron to allow easy cleaning and servicing.

10 Other objects and features of the invention will be made apparent from the following description with reference to the accompanying drawings, wherein:

Fig. 1 is a miniature side elevational view of a steam iron constructed according to the present invention;

Fig. 2 is a part elevational and part sectional view of the iron, the sectional illustration being taken longitudinal of the iron substantially along the longitudinal axis thereof;

Fig. 3 is a fragmentary cross-sectional view taken along line 3—3 of Fig. 2;

Fig. 4 is a plan view of the sole plate portion of the iron with the upper parts of the iron removed, showing more clearly the structure provided by the present invention;

Fig. 5 is a bottom view of the sole plate;

Fig. 6 is a perspective view of the removable plug which is provided in accordance with the present invention; and

Fig. 7 is an enlarged sectional illustration of a part of the structure provided by the invention.

The preferred general form of the iron is shown in Fig. 1, the iron being of the type disclosed in the above-mentioned Stevenson et al. application, and being adapted to be supplied with water from a reservoir (not shown) attachable to the rear of the iron, as disclosed and claimed in the said co-pending application. The iron comprises a sole plate 10, a cover or shell 11 and a handle 12. It is also provided with a support 13, as shown in Figs. 2, 3, and 5 and as shown more clearly in the said co-pending application. By means of such support, the iron may be supported in a tilted position during periods of non-use. The support 13 is pivoted at 14, and a spring 15 serves to urge the iron to its tilted position in response to operation of latching means (not visible) in the handle. The aforementioned structure is briefly mentioned herein merely because the present invention is particularly applicable to such an iron, although it is not limited thereto.

As shown in Figs. 2, 3, and 4, the sole plate 10 is preferably heated by means of an electrical

heating element 16 disposed in a recess 17 and extending about the outer part of the sole plate, as clearly shown in Fig. 4. Such arrangement is not new per se but it is here utilized in cooperation with the novel structure provided by the present invention as hereinafter described.

Referring now to Figs. 2 and 4, an inlet tube 18 is provided at the rear of the iron and is adapted to receive water from a reservoir (not shown) removably attachable to the rear of the iron as disclosed in the above-mentioned co-pending application. The tube 18 extends into a larger tube 19 and is supported by the latter tube as well as by the projecting rear portion 20 of the iron. The tube 19, which is of substantial length, delivers the water through a nozzle 21 to a small water well or reservoir 22 formed in the steam chamber 25 of the sole plate 10. The well 22 is provided with a raised bottom 22a (see Fig. 7) in the form of a very thin wafer-like element of low-heat conductivity metal such as stainless steel. This element is in contact with the metal of the sole plate only at its periphery, and it provides ample heat insulation of the well to prevent steam generation in the well, as will be further explained later. The nozzle 21 is so located in the well 22 as to be beneath the surface of the water therein when the iron is in use and when water is flowing from the reservoir (not shown).

The forward wall 23 of the well 22 is provided with a central recess 24 (see Fig. 3) which serves as a weir and through which water flows from the well 22 to a serpentine or tortuous passage presently to be described. The capacity of the well 22 is such that any surging increase in pressure in the steam chamber 25, which might result from a small amount of water being splashed over the forward wall 23 because of inertia forces as the iron is moved forward and backward, is more than the nozzle 21 can pass back into the tube 19 during the momentary pressure increase in the steam chamber. In other words, the quantity of water from the well 22 which could be forced back through the nozzle 21 into the tube 19, because of any short-lived pressure increase in the steam chamber 25, is less than the quantity of water in the well 22 above the outlet opening of the nozzle 21.

The trough-like weir 24 communicates with the above-mentioned serpentine passage which comprises a plurality of stepped transverse passages 26, 27, and 28 formed in an inclined portion 29 of the sole plate, the transverse runs of the passage being interconnected by grooves 30 and 31. As the water flows through the serpentine passage, it is gradually heated and is vaporized before reaching the floor 32 of the steam chamber. The weir 24 is so designed as to stop the flow of water from the well 22 when the iron is tilted upwardly on the support 13. It should be noted here that the flow of water into the iron is automatically stopped at the reservoir when the iron is tilted upward, as disclosed in the above-mentioned application.

From the description thus far, it will be seen that the steam generating chamber 25 comprises the small well 22, the serpentine passage 26, 27, 28 and the floor area 32. The said chamber is covered by a removable plate 25a which is removed in Fig. 4.

Returning to the water supply tube 19, it will be noted that this tube extends through an apertured wall 33 forming part of the sole plate, and the tube is supported at its forward end by means of a slightly tapered ferrule 34 (see Fig. 7), one

end of which is flanged and is retained by a lip 35 which is formed by an upsetting or staking operation after the ferrule is inserted. The tube 19 is also supported by a washer 36 of low heat-conductivity material such as fibre, which is seated in a recess 37 at the rear of the sole plate, against a shoulder 38. By reason of the fact that the tube 19 is supported in the manner described, both it and the nozzle 21 are prevented from receiving any substantial amount of heat by conduction from the sole plate, and the water passing through the tube and nozzle is thus prevented from being heated to the boiling point. It is very important that the nozzle 21 be kept cool, and this is achieved by the structure described.

The steam generated in the steam chamber 25 is emitted to the ironing surface through a number of passages which are provided by the construction of the sole plate 10 and the removable plug 39. The latter is shaped as illustrated in Fig. 6, having upper recesses 40, a central annular recess 41 and lower recesses 42, all formed in its outer surface. The sole plate is circularly apertured to receive the plug 39 and cooperates with the plug to form the desired steam passages which communicate with grooves 43 (Fig. 5) provided in the lower surface of the sole plate.

The plug 39, which forms a part of the entire sole plate, is recessed at 44 to accommodate the end portion of the support 13. The plug is also centrally recessed to receive a bolt 45 (Fig. 2) by which it is removably secured to the sole plate proper. The head end of the bolt is provided with a flange 46 which seats against an internal shoulder 47 on the plug 39. A pressed steel locking washer 48 serves to hold the plug and bolt together by engaging the flange 46 and by biting into the metal of the plug. The threaded shank of the bolt threadedly engages an insert 49 in the upper part 50 of the sole plate. By a suitable choice of non-ferrous materials for the bolt 45 and the insert 49, the possibility of the plug assembly becoming "frozen" is rendered negligible. It will be seen that when the bolt 45 is turned in a direction to withdraw it from the insert 49, the flange 46 presses against the shoulder 47 and thus forcibly removes the plug. The arrangement thus provided eliminates the objection of prior screw-threaded plugs which have had a tendency to become frozen because of the deposition of soluble salts or minerals from the water on the engaging surfaces.

The construction provided by the invention, as illustrated and described, overcomes the aforementioned objections of prior devices of this type. The provision of small well or reservoir 22 and the associated structure assures a proper and uniform supply of water to the steam generating chamber and hence a uniform supply of steam to the fabric being ironed, during use of the iron and when steam operation of the iron is commenced after a period of use of the iron as a dry iron. The bottom element 22a in the well 22 prevents any appreciable generation of steam therein since it effectively heat insulates the well from the sole plate proper. The rate of heat flow through the side walls of the well to the water therein is not sufficient to raise the water to the boiling point when water is flowing through the nozzle 21 to the well and from the well over the weir 24. When the iron is used dry, or when it is left in tilted position for a considerable length of time with the current on, the bottom element 22a will attain substantially the temperature of the sole plate; but the mass of the

element 22a is so small that the total heat stored therein is dissipated almost immediately when water starts flowing through nozzle 21 and drops on said element. A very small amount of steam may be generated in the well under such conditions, but the well is quickly filled with water and the normal steam generation in the serpentine passages 26, 27 and 28 and on the floor 32 of the steam chamber commences almost immediately.

From the foregoing description, it will be seen that the invention provides a novel steam iron construction which has the various advantages and features hereinbefore mentioned. It will be understood, of course, that the invention is not limited to the structural details of the illustrated embodiment but is susceptible to various modifications such as may be deemed desirable.

We claim:

1. In a steam iron of the type in which water is supplied gravitationally from a water reservoir, a sole plate having steam discharge ports, a steam generating chamber in communication with said ports, a small water well in said chamber, said well having a bottom element engaging the sole plate with low thermal conductivity contact, a passage in said chamber between said well and said ports, and means for conveying water from the supply reservoir to said well, said means having a small opening for discharging water into said well, said opening being disposed at a level to be below the surface of the water in said well during use of the iron.

2. In a steam iron of the type in which water is supplied gravitationally from a water reservoir, a sole plate having steam discharge ports, a steam generating chamber in communication with said ports, a small water well in said chamber, said well including means effectively thermally insulating the well from the sole plate, a passage in said chamber between said well and said ports, and means for conveying water from the supply reservoir to said well, said last-named means having a small opening for discharging water into said well, said opening being disposed at a level to be below the surface of the water in said well during use of the iron.

3. In a steam iron of the type in which water is supplied gravitationally from an external water reservoir at the rear of the iron, a sole plate having steam discharge ports, a steam generating chamber formed in said sole plate approximately midway of the length of the iron, said chamber being in communication with said ports, a small water well in said chamber, a passage in said chamber between said well and said ports, a water feed tube extending from the lower rear of said iron to said well in close proximity to said sole plate, said tube having a small discharge opening which is below the surface of the water in said well during use of the iron, and supporting means for said tube effectively thermally insulating the same from the sole plate to prevent steam generation in said tube while water is flowing therein.

4. In a steam iron of the type in which water is supplied gravitationally from a water reservoir, a sole plate having steam discharge ports, a steam-generating chamber in communication with said ports, a small water well in said chamber, said well including means effectively thermally insulating the well from the sole plate, a passage in said chamber between said well and

said ports, a weir arranged to feed water from said well to said passage, and means for conveying water from the supply reservoir to said well, at least a portion of said last-named means having a small-diameter passageway for discharging water into said well, the outlet of said passageway being disposed at a level to be below the surface of the water in said well during use of the iron.

10 5. In a steam iron of the type in which water is supplied gravitationally from a water reservoir, a sole plate having steam discharge ports, a steam-generating chamber in communication with said ports, a small water well in said chamber, said well including means effectively thermally insulating the well from the sole plate, a serpentine passage in said chamber between said well and said ports, and means for conveying water from the supply reservoir to said well, at least a portion of said last-named means having a small-diameter passageway for discharging water into said well, the outlet of said passageway being disposed at a level to be below the surface of the water in said well during use of the iron.

20 6. In a steam iron, a sole plate, a removable plug forming part of said sole plate, said plug having recesses forming steam passages and also having a central aperture with an upwardly-facing shoulder therein, a securing bolt threadedly engaging a part of the iron and associated with said plug, said bolt having a head seated in the central aperture of the plug and engaging said shoulder so as to forcibly eject said plug from the sole plate when the bolt is withdrawn, and locking means in said central aperture for retaining the bolt head therein.

25 7. In a steam iron of the type in which water is supplied gravitationally from an external water reservoir at the rear of the iron, a sole plate having steam discharge ports, steam generating surfaces within said sole plate in communication with said ports, a relatively long water feed tube extending from the rear of said iron to said surfaces in close proximity to said sole plate, means providing a restricted opening at the discharge end of said tube, and supporting means for said tube effectively thermally insulating the same from the sole plate to prevent steam generation in said tube while water is flowing therein, said supporting means including a member of substantial length surrounding said tube and having one end and a substantial portion of its length spaced from said tube, the said end of said member being disposed in a recess in the sole plate and held therein, the other end of said member engaging said tube and furnishing support therefor.
